CALCULATING MACHINE

Edward C. Walter, Orange, N. J., assignor to
 Monroe Calculating Machine Company,
 Orange, N. J., a corporation of Delaware

Application January 22, 1936, Serial No. 60,176

5 Claims. (Cl. 235—133)

The invention has relation to calculating machines, and more particularly to tens carry mechanism therefor, the present application being a continuation in part of application Serial No. 5 21,724, filed May 16, 1935. The invention consists in the novel construction and combination of parts as set forth in the appended claims.

In the accompanying drawing, illustrating the invention:

10 Fig. 1 is a vertical sectional view through the carry mechanism and associated parts, the members being shown in normal position of rest, with the carry elements restored to inactive position.

15 Fig. 1a is a detail fragmentary section, showing the carry setting spring.

Fig. 2 is a plan view of a carry mechanism with the parts shown in the positions assumed in transferring a unit to a higher order numeral wheel.

20 Fig. 3 is a sectional view, taken on the line 3—3 of Fig. 1, showing the carry elements in inactive position.

Fig. 4 is a similar view, showing a modified form of carry dog.

25 In this drawing the invention is illustrated as applied to a machine of the Monroe type, illustrated in United States Patent No. 1,474,230, granted to E. F. Britten, Jr. on November 13, 1923. In this machine the differentially set actuators and the tens carry elements are mounted 30 upon separate shafts which shafts are rotated in one direction for performing positive or additive calculations and in the opposite direction for performing negative or subtractive calculations. The 35 tens carry mechanism is of the pre-set type.

In the drawing, the numeral 1 designates a numeral wheel, of which a series is provided, mounted upon the shaft 2, and each having fast therewith a pinion 3, adapted to mesh with an 40 intermediate gear 4, which gear is operated by the differentially set actuators and by the tens carry mechanism. Each wheel 3 is provided with a projection 5 lying in the plane of a tooth 6 of a settable carry member 7 pivoted at 8 upon 45 a supporting shaft and provided with a toggle spring 9 adapted to hold the member 7 in either of two set positions; with the tooth 6 in the path of movement of the projection 5, or upon displacement of the member 7 by projection 5 to hold an oppositely beveled surface 12 of member 7 in depressed position. There is a settable 50 member 7 related to each active numeral wheel 1 of the machine.

Upon the drive shaft 13 are splined a series of 55 circumferentially channeled sleeves 14, each sleeve

being provided with two radial notches in which are mounted two pivotal dogs 15 extending longitudinally of shaft 13, one of said dogs acting to transmit the carry to the next higher wheel in additive operations and the other in subtractive operations. The additive and subtractive carry dogs 15 of the series of sleeves 14 are angularly offset from one another, to form two opposed spiral series of dogs, in the well-known manner.

Preferably each pair of dogs 15 is secured upon the sleeve 14 by an annular spring 16, seated in a channel of the sleeve and passing through a perforation intermediate the ends of the dogs 15. In Figs. 2 and 3 this spring is shown as helically wound, but a segmental clip spring 10 may be 15 employed as illustrated in Fig. 4. A similar annular helical spring 17 is seated in a second channel of the sleeve, and engages the outer edges of the dogs 15 to hold them normally in inactive position. If tightly wound, spring 17 will lie upon 20 the top of the dog, as shown in Figs. 2 and 3, while if loosely wound, the dog will enter between the coils, as in Fig. 4.

Each dog 15 is comprised of two diametrically opposite arms, one arm being carried, in the rotation of shaft 13, past the place occupied by the beveled surface 12 when the related member 7 is held in active position, this arm of the dog being depressed by the action of the cam surface, the opposite arm being thereby raised into position to 25 engage between the teeth of the intermediate gear 4 related to the next higher order numeral wheel. The dog is held in engaging position while passing through the gear, so that one step of movement is imparted to the higher order wheel, after which the dog, passing beyond the surface 30 12, will be retracted by its spring 17.

Double beveled tooth 20, formed upon the sleeve 14 will engage a pin 21 of member 7, acting to 35 cam the member into fully raised position.

A dog 15 having been rocked into active position and brought into contact with a tooth of gear 4, there will be a reactive tendency against the yieldable toggle spring 9. A large part of this reactive thrust, however, is taken up by friction, 45 since the dog will be rocked sidewise, by contact with the gear tooth, into engagement with the opposite shoulders of the radial notch of the sleeve in which the dog is mounted. Springs 9, therefore, need not be stiff enough to provide undue 50 resistance to movement of member 7.

It is to be noted that the dogs 15 are pivoted at points lying in the plane of the pitch diameter of gears 4, hence the dogs engage the teeth of the gears by a radial movement, this meshing being 55

possible before the intermediate gears have come fully to rest, without interference between the dog and the tooth of the gear. It is also to be noted that in high speed operation, with the dogs 5 15 of the spiral series separated from each other by a very slight angular displacement about shaft 13, a dog 15 may be engaged between the teeth of the related intermediate gear while the settable member 7 is being moved down against the opposite end of the dog. Because of this latter arrangement, permitting the dogs 15 to be separated from one another angularly by a very slight distance, they may be mounted close to the driving shaft 13, having, as shown, the same radial extent 10 15 as the differentially set actuators 22 of the machine. This will obviously reduce the peripheral speed of the dogs 15 and consequently will reduce the speed of the entire carry movement.

I claim:

- 20 1. In a tens carry mechanism for calculating machines, the combination with numeral wheels provided with projections, gears related to said wheels, and a settable member adapted to be displaced by a projection as the related wheel moves between 9 and 0 registering position; of a drive shaft, and an intermediately pivoted dog comprising diametrically opposed arms mounted for rotation with said shaft, engageable at the end of one arm by the settable member and 25 adapted to be rocked by a numeral wheel in movement transmitted through said member, to move its opposite arm radially of and into position to contact the gear related to the numeral wheel of next higher order.
- 30 2. In a tens carry mechanism for calculating machines, the combination with numeral wheels provided with projections, gears related to said wheels, a settable member adapted to be displaced by a projection as the related wheel moves 35 between 9 and 0 registering position, and spring means acting to hold said member yieldably in either of two positions; of a drive shaft, a sleeve fixed upon said shaft and having opposed shoulders, and a dog pivotally mounted upon said 40 sleeve at a point in the plane of the pitch diameter of said gears and extending longitudinally of the shaft between said shoulders, said dog being 45 engageable by the settable member and movable thereby radially of and into position to contact

the gear related to the numeral wheel of next higher order.

3. In a tens carry mechanism for calculating machines, the combination with numeral wheels provided with projections, gears related to said wheels, and a settable member adapted to be displaced by a projection as the related wheel moves between 9 and 0 registering position; of a drive shaft, a pivoted dog mounted for rotation with said shaft, engageable by the settable member and movable thereby radially of and into position to contact the gear related to the numeral wheel of next higher order, and an annular spring surrounding said shaft and engaging the dog, to resist radial movement thereof. 5 10 15

4. In a tens carry mechanism for calculating machines, the combination with numeral wheels provided with projections, gears related to said wheels, and a settable member adapted to be displaced by a projection as the related wheel moves between 9 and 0 registering position; of a drive shaft, two pivoted dogs mounted for rotation with said shaft in the same plane, engageable by the settable member and movable thereby radially of and into position to contact the gear related to the numeral wheel of next higher order, and an annular spring surrounding said shaft and engaging both said dogs, to resist radial movement thereof. 20 25

5. In a tens carry mechanism for calculating machines, the combination with numeral wheels provided with projections, gears related to said wheels, and a settable member adapted to be displaced by a projection as the related wheel moves between 9 and 0 registering position; of a drive shaft, a circumferentially channelled radially notched sleeve fixed upon said shaft, a perforated dog mounted in the notch of said sleeve, an annular spring seated in a channel of said sleeve and passing through the perforation of said dog, and a second annular spring seated in a channel of said sleeve and engaging the dog, to resist rocking movement thereof, said dog being engageable by the settable member and adapted to be rocked thereby radially of and into position to contact the gear related to the numeral wheel of next higher order. 30 35 40 45

EDWARD C. WALTER.
